UNITED STATES PATENT OFFICE.

GUSTAV B. PETSCHÉ, OF PHILADELPHIA, PENNSYLVANIA, ASSIGNOR TO SOUTHWARK FOUNDRY AND MACHINE COMPANY, OF PHILADELPHIA, PENNSYLVANIA, A CORPORATION OF PENNSYLVANIA.

CONDENSER.

947,845.

Specification of Letters Patent.

Patented Feb. 1, 1910.

Application filed March 7, 1906. Serial No. 304,628.

To all whom it may concern:
Be it known that I, GUSTAV B. PETSCHÉ, a subject of the Emperor of Germany, residing in the city and county of Philadelphia, in the State of Pennsylvania, have invented a certain new and useful Improvement in Condensers, of which the following is a true and exact description, reference being had to the accompanying drawings, which form a part thereof.

My invention relates to condensers of the general character of the condenser described in the patent to Weiss, reissue 11,591 of March 2nd, 1897, in which condenser the steam is condensed generally by a counter current mode of operation, but sometimes by a parallel current mode of operation, means being provided for interrupting the vacuum when the condenser works by parallel currents and thus restoring it to normal counter current operation.

The object of my invention is chiefly to provide improved means for interrupting the vacuum and restoring the normal counter current operation in the apparatus, but I also have in view the general improvement of condensers of this kind.

The nature of my improvements will be best understood as described in connection with the drawings in which they are illustrated, in which—

Figure 1 is a side elevation of my improved condenser. Fig. 2, a sectional elevation on the line 2—2 of Fig. 1. Fig. 3, a plan view of the head of the separation chamber with the top of the air chamber removed. Fig. 4 is a cross-sectional view through the air chamber taken as on the line 4—4 of Fig. 3, showing the lid of the air chamber in place. Fig. 5 is a perspective view of the perforated bucket, and Fig. 6 is a perspective view of the air valve and the parts of the valve operating mechanism directly connected therewith.

A is the body of the condenser, B the steam inlet leading into the bottom thereof, C the inlet leading into the top thereof, D an opening for convenient access to the lower part of the condenser body, E, E' the water barometer waste pipe connecting with the bottom of the condenser and opening at bottom into a box E², having openings as indicated at E³ at each end, said openings being provided with hinged gates or valves

E⁴. The construction of the box and its valves is the same as that of the box marked H², shown in Fig. 2, and hereinafter described. The box is situated in the waste water well F, which in my improved construction is a closed well provided with a take off pipe F' and a cover F², through which the water barometer pipes pass.

From the top of the condenser body leads the conduit G, an extension G' of which is prolonged into the separation chamber H, as shown in Fig. 2. An air pipe I, leads from the top of this separation chamber to an air pump I'. The separation chamber H connects at bottom with a water barometer waste pipe H', which extends down into the waste water well connecting at bottom with a box H² having openings H³ provided with hinged valves H⁴.

To an elbow G² on the pipe G I attach the air chamber J, provided with an air port J', and supporting pivots at J² and J³.

K is the air valve, normally held seated on the air port by some yielding or resilient force, as by being supported on the cross bar K' of the levers K², K³ pivoted at J³, and provided with a counterweight K⁴. The valve has also attached to it the rod L, which is connected with the end of the lever L', pivoted in the air box at J², and connected at an intermediate point with the depending rod L², which extends into the separation chamber, where it is attached to a perforated bucket M, M' indicating the perforation in the bottom of the bucket, and M² guide plates secured to the walls of the separation chamber and serving to steady the perforated bucket. A pipe J⁴ connects with the air box J, and leads into the head of the condenser chamber, as shown in Fig. 2.

To return to the detailed construction of the condenser chamber, it will be seen that the water inlet C leads into an annular water chamber A' in the top of the condenser, an annular rim A² being provided at the top of the chamber and formed to direct the overflow of the water inwardly toward the center of the chamber, where it flows against a conical baffle plate A³, provided with perforations, through which a portion of the water is directed inward, while another portion flowing over the baffle plate is directed outward, as shown, and flows down until it comes in contact with the annular conical

flange or baffle plate A⁸, also provided with perforations through which a portion of the water flows downward while the remainder of the water is directed inwardly 5 to the perforated dish-like baffle plate indicated at A⁷. A tubular extension A⁹ extends up from the dish A⁷, and a tubular extension A⁴ extends upward from the top of the conical baffle plate A⁶, and at the bottom of the 10 condenser chamber I provide the upwardly converging flange A⁸, to insure that the water shall fall into the upper end of the waste pipe E out of contact with the sides of the pipe.

15 By inclosing the waste water well F, I avoid objectionable features of similar condensers owing to the splashing of water and occasional ebullitions of steam, and by placing the device which covers the mechanism for breaking the vacuum in the separation chamber I also avoid the splashing of water outside of the condensing apparatus as well as protect the mechanism by placing it beyond the reach of ordinary accidents.

20 In normal operation, my condenser works by counter currents, the water passing down into the waste pipe E, E', and the air upward through the pipe G into the separator H, and thence through pipe I to the air pump, the separated water flowing downward into the waste pipe H', and being normally in such volume that whatever portion is caught in the pail M runs freely out of the 25 perforation M'. Where the water is heated in the condenser body to a point where it will pass upward with the air and steam instead of downward, it rushes into the separation chamber H, in such volume as to fill the perforated pail M, the weight of which 30 when filled with water is sufficient to overcome the counterbalance K^a, and draw the air valve K downward, permitting air to enter the air box through the port J', whence it passes into the pipe G and also through 35 the pipe J^a into the head of the condenser body, breaking the vacuum in the condenser to such a point that the water will no longer pass upward with the steam and thus 40 restoring the condenser to normal counter current operation.

45 The baffle plate system of the condenser body has already been sufficiently described and is clearly indicated by the lines indicating the flow of water in the drawing, Fig. 2.

50 Having now described my invention, what I claim as new and desire to secure by Letters Patent is:

1. In a condenser of the character described adapted to operate either as a parallel current or counter current condenser, the combination with the condensing chamber and the conduit through which the water passes from the condensing chamber when the condenser is working as a parallel current condenser, of means for temporarily

breaking the vacuum in the condenser, and an actuating device for said means comprising a perforated pail situated in said conduit above the level to which water accumulates therein, and normally held in a fixed 70 non-operative position by a yielding force, said pail being arranged to be urged in the same direction out of said non-operative position by the direct impact against the pail of the water passing through said conduit 75 and by the weight of the water accumulating in said pail.

2. In a condenser having a body connecting at bottom with a waste water barometer pipe and at top with both an air pump and 80 a waste water barometer pipe through a separating chamber, and having means for temporarily interrupting the vacuum in the condensing body, a device for operating said means to break the vacuum consisting of a 85 perforated pail situated in the separator chamber and normally held in fixed non-operative position by a yielding force, said pail being arranged so that it is urged in the same direction away from said non-operative 90 position by the direct impact of the water passing through the separator chamber and by the accumulation of water in the pail.

3. In a condenser of the character described having waste water barometer pipes 95 connected with both the bottom and top of the condenser body, a closed waste water well into which both of said barometer pipes open, means for temporarily breaking the vacuum in the condenser, and a device for 100 actuating said means comprising a perforated pail situated in a conduit leading from the top of the condenser to the barometer pipe connected therewith and adapted to be actuated when there is an excessive flow of 105 water through said conduit by the direct impact of water flowing through said conduit and by the weight of the water accumulating in said pail.

4. In a condenser of the character described having waste water barometer pipes connected with both the bottom and top of the condenser body, the latter connection being through a separator chamber connected also to a vacuum pump, a closed waste water well into which both of said barometer pipes open, means for temporarily breaking the vacuum in the condenser and a device for actuating said means consisting of a perforated pail suspended and guided for vertical 110 movement in the separator but normally held in a fixed non-operative position by a yielding force, said pail being urged downward by the direct impact of water passing through said separator and also by the weight of water accumulating in said pail when an excessive flow of water through the separator takes place.

5. In a condenser of the character described, having waste water barometer pipes 115

connected with both the bottom and top of the condenser body, a closed waste water well into which both of said barometer pipes open, through boxes E², H², having hinged gates E⁴, H⁴, means for temporarily breaking the vacuum in the condenser, and a device for actuating said means, comprising a leaky pail, situated in a conduit leading from the top of the condenser to the barometer pipe connected therewith above the level to which water accumulates in said conduit and adapted to be actuated, when an excessive flow of water through said conduit occurs, by the direct impact of water flowing through the conduit and the weight of water accumulating in said pail.

6. In a condenser of the character described and having an outlet conduit G leading from its top and connecting through a separator chamber with a water barometer waste pipe and a vacuum pump, a chamber

J, connected to conduit G, and having an air inlet port J', a valve K, for closing said port, means for holding said valve normally seated, a lever L', situated in chamber J, and connected to the valve, a rod L², depending from said lever into the separator chamber and a perforated pail secured to said rod.

7. In a condenser of the character described a body A, having a steam inlet near its bottom and an annular water chamber A', near its top in combination with a perforated conical baffle plate A⁶, placed to remove the water flowing from the annular chamber, a perforated conical baffle plate A⁸, situated below the baffle A⁶, and a perforated baffle pan A⁷, placed to remove the water passing through the baffle A⁶.
